KITCHEN VENTILATOR

Filed Dec. 4, 1936

Fig. 3. Bernhard Sonntag,

INVENTOR.

BY John M. Spellman

ATTORNEY.

UNITED STATES PATENT OFFICE

2,077,496

KITCHEN VENTILATOR

Bernhard Sonntag, Dallas, Tex.

Application December 4, 1936, Serial No. 114,157

4 Claims. (Cl. 98—115)

My invention relates to ventilators of a type used to carry away cooking odors, smoke, heat and grease-laden fumes from kitchens, gas ranges and stoves used for similar purposes.

5 In this connection, one of the principal objects of the invention is the provision of a ventilator of the type referred to and adaptable to any kitchen of the home or elsewhere wherever a flue and electrical service are available, and which may 10 be installed at a minimum of cost.

Another object of the invention is the novel and simple construction of the ventilator and wherein the exhausting unit and the smoke deflector are capable of easy removal for the purpose of cleaning, inspection or replacement.

Another important object of the invention is the construction and arrangement of the smoke deflector, said deflector permitting the suction of air to draw the smoke and fumes over the entire 20 area of the inside of the hood.

With the foregoing and other objects in view the invention will be clearly understood from a perusal of the following detailed description, taken in connection with the accompanying 25 drawing, and wherein:

Figure 1 represents a perspective view in part of a gas cooking range and a ventilator and illustrating an embodiment of the invention, the ventilator hood being partly broken away.

30 Figure 2 is a vertical transverse sectional view through the hood in Figure 1, showing in detail the various parts of the ventilator.

Figure 3 represents a top plan view of Figure 2 of the smoke deflector and exhaust unit, the hood 35 not shown.

Figure 4 represents a vertical sectional detail view of Figure 3, the view being taken on the line 4—4 thereof, and showing the exhaust unit, and

Figure 5 is a front elevational view of the exhaust unit housing cover plate.

Referring more in detail to the drawing, like parts being designated by like characters, I indicate a gas or similar cooking range of modern type, although the ventilator is adaptable to any 45 type of cooking stove where a flue outlet and electrical service are available. The ventilator consists of a backboard or support 2 and a hood 3, these parts being adaptable to installation in kitchens of new or old dwellings and apartments 50 and being secured to the kitchen wall by the screws 3a. Connected to the hood 3 is a vent pipe 4 which leads to the flue of the house or dwelling.

55 Secured to the board 2 is the hood 3 with the lateral panels 5, these parts being positioned above

the burners so as to catch and direct the smoke and fumes into the exhaust unit.

As illustrated more clearly in Figure 2 the exhaust unit consists of a powerful centrifugal blower 6, not merely an electric fan, so that the blower is positive in action and has a suction equal to that of a large exhaust fan. This blower is quiet in action and is operated by an electric motor 7 through the motor shaft 8 upon which the blower is mounted.

10 The motor 7 and blower 6 are enclosed in a housing consisting of a bottom wall or support 12, secured by screws to the backboard or support 2, a rear wall 10, side walls 10a and a removable cover plate 11. The cover plate is shown by itself 15 in Figure 5.

The horizontal partition walls 12, 13, and vertical wall 13a and the curved portion 13b thus complete the closure for the blower and enable the air suction, created by the blower, and as indicated by the arrows, to flow into this closure through the opening 14 and exhaust into the flue pipe 4 through the vent 15. As shown in Figure 3, the side walls 10a are bent at right angles 20 to provide a flange 10b for fastening these walls 25 to the hood 3.

A conduit pipe 17 with light globe 18 and pull cord 19 provide lighting facilities and a pull cord 20 starts and stops the motor 7. A bracket 21 supports the conduit on the wall 10. The cover plate 11 includes a rounded notch 23 to receive the conduit pipe 17 and the cover plate is also provided with apertures 24 which fasten over the stud bolts 25, welded to the side walls 10a, and the wing nuts 26 hold the cover plate in position. Consequently the cover plate may be easily 30 removed by taking off the wing nuts and the blower and adjacent parts cleaned, inspected, or 35 parts replaced.

In addition to the foregoing I provide a smoke 40 deflector with upwardly slanting walls 27 and 28, the upper edges of which extend on a line midway across the opening 14 in the cover plate 11, leaving a narrow opening for smoke and fumes to pass over its edges to the blower. As shown by 45 the arrows, Figure 2, the smoke and grease-laden fumes are thus deflected upwardly. The smoke deflector is an important feature of my invention and provides a means whereby the suction from the blower is spread over the entire area 50 of the inside of the hood. The smoke deflector is secured to the bottom wall 12 by stud bolts and wing nuts 30, making it easily removable for cleaning, inspection or replacement of parts.

55 While I have shown and described a practical

working embodiment of my invention, it is apparent that parts thereof may be modified, altered and changed, without departing from the intent of the invention, and within the scope and meaning of the appended claims.

What I claim as new is:

1. A ventilator of the class described and adapted to be used with a hood, said ventilator comprising a housing having a rearwardly projecting support, a centrifugal blower for creating air suction, and electric motor mounted on the said projecting support for operating said blower, the blower being inclosed by the housing, said housing including a bottom wall, a top wall, side walls, and a rear partition wall, said partition wall separating the motor and blower, a removable cover plate for the housing, said plate having an opening for inlet of smoke and fumes, and said top wall having an opening for exhaust of said fumes and smoke, and including a smoke deflecting means projecting outwardly and upwardly from the lower part of the said housing.

2. A ventilator of the class described in combination with a hood, the said ventilator comprising a housing having a rearwardly projecting support, a centrifugal blower in the housing, an electric motor for operating said blower mounted on the said support, a smoke deflecting means comprising an apron removably secured to the lower portion of said housing and directed outwardly and upwardly, the upper edges of said apron being disposed below and inside the surface of the said

hood to be used with the ventilator and providing a space for entrance of smoke and the like to be drawn into the said housing, and a removable cover plate for the housing.

3. A ventilator of the class described and in combination with a hood, said ventilator comprising a housing having a rearwardly projecting support, a centrifugal blower for creating air suction, an electric motor mounted on the said projecting support for operating said blower, the blower being inclosed by the housing, said housing including a bottom wall, a top wall, side walls, and a rear partition wall, said partition wall separating the motor and blower, a removable cover plate for the housing, said plate having an opening for inlet of smoke and fumes, and said top wall having an opening for exhaust of said fumes and smoke, and a smoke deflecting means comprising an apron removably secured to the lower portion of said housing and directed outwardly and upwardly therefrom within the area of the hood, the upper edges of said apron being disposed below the inside surface of said hood and providing a space for entrance of smoke and the like to be drawn into said opening of said cover plate.

4. A ventilator of the class described and as claimed in claim 1, said housing including also a curved wall and the said curved wall being accessible by removing the said removable cover.

BERNHARD SONNTAG.
